UNITED STATES PATENT OFFICE

HANS N. HEDEBY, OF YOUNGSTOWN, OHIO

LEAK DETECTOR

Application filed October 7, 1929. Serial No. 397,941.

The present invention appertains to new and useful improvements in circuit makers and breakers of the fluid closing type.

The principal object of this invention is to provide a device in this class of invention particularly adapted for attachment to liquid pipes so that in event of a leak in the pipe, the escaping liquid will complete an alarm circuit.

10 During the course of the following specification and claims numerous other important objects and advantages of the invention will readily become apparent.

In the drawings:

15 Figure 1 represents a pipe equipped with the present invention and diagrammatically disclosing the connections between the electrical devices involved.

Figure 2 represents a top plan view of the 20 pipe attachment.

Figure 3 represents a fragmentary sectional view disclosing the attachment associated with a pipe.

Referring to the drawings, wherein like 25 numerals designate like parts, it will be seen that numeral 5 denotes a pipe to which this invention is to be secured. In carrying out the invention, an annulus 6 of some suitable di-electric material is provided and this annulus is provided with a circumferentially extending shoulder 7 at its upper portion. The upper portion of the annulus is also formed to provide a trough 8 into which the escaping liquid from the pipe 5 may flow.

30 As is clearly shown in Figure 2, the annulus is preferably constructed of a pair of sections to facilitate their application to the pipe 5. A clamp band 9 is employed to circumscribe the lower portion of the annulus and this band is constructed at its free end with a pair of ears 10—10 which assume a position in parallel relation to each other when the band is engaged around the annulus.

45 A bolt 11 and nut 12 are employed for drawing the band 9 tightly against the sections of the annulus. Disposed within the trough 8 are the conductors 13 and 14 and as clearly shown, these conductors are secured 50 to the sections of the annulus by staples 15,

which staples have their free ends anchored or imbedded in the annulus.

As shown in Figure 1, one end of each conductor projects beyond the periphery of the annulus at its shoulder portion 7 while 55 its opposite end is disposed through an eyelet 16 and twisted as at 17.

In conjunction with the aforementioned construction, a clock of electrical type is shown in the drawings and denoted by numeral 18, while a multiple indicator panel 19 is also employed. This panel is of the type provided with a plurality of lamp compartments and lenses covering the same, each 60 having indicating matter thereon, so that 65 when the lamp in the compartment is lighted, the indicating matter will be visible.

It will now be observed that the lamp in each of these compartments is to be connected in circuit with the conductors 13 and 14 70 of one unit. By way of example, the conductor 14 has a connection 20 with one side of the lamp in one of the compartments (indicated 801) while the opposite side of the lamp (not shown) is connected to the positive side of the battery 21 with the negative side of the battery connected to one side of the clock 18 through the jumper 22. As is also shown, a wire 23 extending from the 75 opposite side of the electrical clock connects to each of the conductors 13 employed.

Additional wires 20' are connected to the conductors 14 of other circuit closing units of the same type shown in Figure 1. It will thus be seen that the liquid escapes from the pipe 5 and drips or flows down the pipe, the same will flow into the trough 8 and when sufficient liquid has been collected to bridge the conductors 13 and 14, the circuit will 80 be completed with the designated lamp of the indicating board or panel 19 so that the 85 location of the particular leak may be readily ascertained.

While the foregoing description sets forth 90 the invention in specific terms, it is to be understood that various changes in the shape, size and materials may be resorted to without departing from the spirit and scope of the invention as claimed hereinafter.

Having thus described the invention, what I claim as new is:

1. A circuit closer of the type described comprising an annulus for circumscribing a liquid conduit, said annulus being constructed to provide a trough for collecting liquid escaping from the said conduit, and contacts mounted within the trough of the said annulus.
- 10 2. A circuit closer of the type described comprising a sectional annulus for disposition around a liquid conduit, clamp means for securing the annulus snugly to the pipe, and contacts on the said annulus adapted to be bridged by liquid escaping from the said conduit.
- 20 3. A circuit closer of the type described comprising an annulus divided into a pair of sections, a clamp band for circumscribing the annulus and snugly securing the same to a liquid conduit, said annulus being constructed to provide a trough, and a pair of conductors disposed within the trough and in spaced relation with respect to each other
- 25 4. A circuit closer of the type described comprising an annulus divided into a pair of sections, a clamp band for circumscribing the annulus and snugly securing the same to a liquid conduit, said annulus being constructed to provide a trough, and a pair of conductors disposed within the trough and in spaced relation with respect to each other
- 35 and being adapted to be bridged by liquid in the said trough of the annulus.
4. A circuit closer of the type described comprising an annulus divided into a pair of sections, a clamp band for circumscribing the annulus and snugly securing the same to a liquid conduit, said annulus being constructed to provide a trough, and a pair of conductors disposed within the trough and in spaced relation with respect to each other
- 35 and being adapted to be bridged by liquid in the said trough of the annulus, said annulus being constructed of a di-electric material.

In testimony whereof I affix my signature.

HANS N. HEDEBY.
